Patented Mar. 10, 1914

UNITED STATES PATENT OFFICE.

KURT GREUNER, OF ESSEN-ON-THE-RUHR, GERMANY, ASSIGNOR TO FRIED. KRUPP AKTIENGESELLSCHAFT, OF ESSEN-ON-THE-RUHR, GERMANY.

CONTINUOUS-CURRENT GENERATOR.

1,090,048.

Specification of Letters Patent. Patented Mar. 10, 1914.

Application filed May 15, 1911. Serial No. 627,154.

To all whom it may concern:

Be it known that I, KURT GREUNER, a subject of the Emperor of Germany, and a resident of Essen-on-the-Ruhr, Germany, 5 have invented certain new and useful Improvements in Continuous-Current Generators, of which the following is a specification.

In operating electro-motors which are arranged in so called Leonard-connection and are fed by a separately excited generator with compounding winding, it is desirable that the motor, even in its unloaded state, with certainty stands still when the separate excitation is cut off; and also that the remanent current which appears when the motor stands still may become as small as possible.

Figures 1 and 2 give diagrammatical representations of the currents; Fig. 3 gives an embodiment of the invention representing a longitudinal section of the generator; and Fig. 4 front and rear-end views of Fig. 3.

The conditions obtained with disconnected separate excitation are diagrammatically shown in Fig. 1 on the drawing. The abscissas measured in the direction of the axis M A express the strength of the armature current of the generator, and the ordinates measured in the direction of the axis M B, the magnitude of the corresponding tension. If the generator has no other field-winding beside the separately excited winding and the compounding winding, it will deliver an electromotive force which is a combination of the remanent tension and the tension generated by the compounding winding. The remanent tension is in Fig. 1 10 expressed by a line c, parallel to the abscissa-axis M A and intersecting the ordinate axis M B at the point C. The curve d, Fig. 2, represents the characteristic of the compounding winding relative to the strength 15 of the armature current, and has been drawn in the usual manner as regards the coördinate system A' M' B', which corresponds to the coördinate system A M B in Fig. 1. Drawing now this curve d in the same relation to lines c and C B in Fig. 1, as it has to the coördinate axes M' A' and M' B' in Fig. 2, a curve d' will be produced, the ordinates of which will represent 20 the sum of the remanent tension and the tension generated by the compounding wind-

ing. In other words, it represents the course of the electromotive force of the generator with the separate excitation cut out. The curve d' intersects at a point F a straight line e running through the origin M of co-ordinates, which line represents the voltage drop, caused by the resistance of the circuit; and which line will briefly be called "resistance line"; the abscissa M G of this point F representing the greatest current strength 60 which would be obtainable with disconnected separate excitation. Should the strength of the armature current represented by the abscissa M G be smaller than that of the current expressing the starting 65 moment of the motor, the motor will be at rest when the separate excitation is disconnected, and a remanent current will be produced, the magnitude of which is represented by the length of M G.

In order to get the remanent current as small as possible, which is very desirable, it must be so arranged that the intersection between the resistance line and the curve (representing the course of the electromotive force of the generator with the separate excitation cut out) is situated as near as possible to the starting point M of the co-ordinates. To accomplish this, a differential compound winding to weaken the field 70 has before now been used.

The present invention relates to an arrangement of this kind of generators, wherein the desired object can be reached in a more complete way.

The present invention consists in arranging the differential compound winding on a separate magnet frame, the saturation point of which has been chosen so low that the field strength of this magnet frame is 80 influenced by the exciting current of the opposing winding only up to a comparatively low current strength.

Figs. 3 and 4 give a diagrammatical representation of one embodiment of the invention, of which Fig. 3 represents a longitudinal section of the generator and Fig. 4 front and rear end views. H represents the principal magnet frame with the separately excited field-winding N and the compounding winding D, and J represents the special magnet frame carrying the differential compound winding K for weakening the field. As indicated in Fig. 4, the windings D and K are arranged in series. The saturation 90

point of the magnet frame J lies so low, that the field strength of this magnet frame is substantially influenced only up to a comparatively low current strength by the exciting current of the differential compound winding K. In consequence hereof the characteristic of the differential compound winding K, referred to the strength of the armature current, runs almost parallel to the abscissa-axis M' A', starting from a comparatively low value of the current strength. This is shown in Fig. 2, the course being indicated by the curve k, drawn in the same direction as the characteristic d of the compound winding D. The sections of the ordinates lying between these curves d and k represent the ordinates of the resultant characteristic of the windings D and K. The resultant characteristic of the windings D and K will then be represented by a curve n obtained by laying off against the abscissa-axis M' A' the lengths of the ordinates cut off between curves d and k. The proportion is so chosen that the characteristic k in the beginning runs steeper than the characteristic d so that the corresponding part of the resultant characteristic n will have negative ordinates. If now the curve n is laid off against lines e and C B in Fig. 1, in a similar position to what it has in Fig. 2 relative to the coördinate axes M' A' and M' B', a curve n' will be obtained, that represents the resultant electromotive force produced in a generator provided with compound and differential compound windings and having the separate excitation disconnected. With the highest possible remanent tension, represented by the line e, it would still be possible, as Fig. 1 shows, to attain that the curve n' intersects the resistance line e in a point F', lying very close to the beginning M of the coördinates; and that beyond the point F', it continues to run below the resistance line e. It is particularly advantageous in this relation, when the proportions, as indicated above, are so chosen, that the characteristic k of the differential compound winding, to commence with, runs steeper than the characteristic d of the compounding winding so that the resulting characteristic n runs at first below the abscissa-axis M' A'. As the intersecting point F' is situated very close to the starting point M of the coördinates, the remanent current represented by the abscissa M G' of the point F' will be exceedingly small, and the smaller the remanent tension is, the smaller said current will be, which may be easily seen from Fig. 1. It is also desirable to choose the proportion in such a manner that the curve n' on the other side of point F' runs as near as possible parallel to the resistance line e. In that case, a curve p, Fig. 1, will be obtained of the resultant electromotive force of the generator

when the separate excitation is connected, which curve p will run as nearly parallel to the resistance line e as the curve n', its ordinates being proportionately larger than the corresponding ordinates of the curve n'. 70 This circumstance is particularly advantageous if the motor has to run with very low speed (with few revolutions per minute). In the case illustrated in Fig. 1, the curve p within the range in question, is situated only very slightly above the resistance line e, proportionate to the number of revolutions of the motor. If the curve p does not run approximately parallel to the resistance line e, even a slight change in load would have a considerable influence on the number 80 of revolutions of the motor (the motor speed) and in some cases would cause a sudden stopping of the motor. If, on the other hand, the curve p runs approximately parallel to the resistance line e, the influence of the above mentioned irregularities will be of but little importance, and as a consequence a safe and uniform running of the motor is guaranteed even with very low 90 speed.

The present invention possesses still another advantage over the ordinary generators, namely that it is possible to couple the differential compound winding with the 95 compounding winding in series. A similar simple coupling is not applicable in ordinary generators; as, with such a coupling, the same effect would simply be attained as if the generator, beside the separated excitation had but one compounding winding with correspondingly fewer number of coils. 100

What is claimed is:—

1. In a separately excited continuous current generator, having separately excited 105 winding a compounding winding and a differential winding for weakening the field: a main magnet-frame carrying said compounding winding and a separate magnet-frame carrying said differential winding, 110 the saturation point of said last-named magnet-frame being considerably lower than that of the first-named one.

2. In a separately excited continuous current generator, having separately excited 115 winding a compounding winding and a differential winding connected in series therewith for weakening the field; a main magnet-frame carrying said compounding winding and a separate magnet-frame carrying 120 said differential winding, the saturation point of said last-named magnet-frame being considerably lower than that of the first-named one.

3. In a separately excited continuous current generator, having separately excited winding a compounding winding and a differential winding for weakening the field, a main magnet-frame carrying said compounding winding and a separate magnet- 125 130

frame carrying said differential winding, the saturation point of said last-named magnet-frame being considerably lower than that of the first-named one and the characteristic curve of the differential winding, representing the functional relation existing between the electromotive force induced by said winding and the armature current strength, being steeper near the starting

point than the corresponding characteristic 10 curve of the compound winding.

The foregoing specification signed at Bar-
men, Germany, this 2nd day of May, 1911.
